(57) **CLAIM**

The ornamental design for an inspection lamp, as shown and described.

DESCRIPTION

FIG. 1 is a rear perspective view of an inspection lamp, showing my new design;

FIG. 2 is a top view thereof;

FIG. 3 is a bottom view thereof;

FIG. 4 is a rear view thereof;

FIG. 5 is a left side view thereof, the right side view being identical; and,

FIG. 6 is a front view thereof.

The broken lines are shown for environmental purposes only and form no part of the claimed design.
